UNITED STATES PATENT OFFICE.

WILLIAM DAVEY ODDY, OF LEEDS, ENGLAND, ASSIGNOR OF ONE-HALF TO HENRY RICHMOND AND SONS, LIMITED, OF LEEDS, ENGLAND.

FOUNDRY MOLDING-MACHINE.

1,137,658.

Specification of Letters Patent. Patented Apr. 27, 1915.

Application filed September 15, 1913. Serial No. 789,763.

To all whom it may concern:

Be it known that I, WILLIAM DAVEY ODDY, a subject of the King of Great Britain and Ireland, residing at Leeds, in the county of 5 York, England, have invented certain new and useful Improvements in Foundry Molding-Machines, of which the following is a specification.

This invention relates to foundry molding 10 machines used for the production in quantity of molds of exactly similar pattern, and has for its object to obtain greater uniformity in the density of the sand, notwithstanding that molds may be of considerable 15 thickness or depth, and may be of considerable variation in contour.

This invention consists in a construction 20 of machine such that the filling and pressing of the sand into and in the mold boxes takes place automatically in successive stages, that is, a portion only of the sand required to fill the mold is introduced and then pressed, after which a second portion is introduced and pressed and so on till the mold is filled.

25 The invention is hereunder illustrated by and described with reference to the accompanying drawings, in which—

Figure 1 is a plan, and Fig. 2 is a vertical section on lines A O and O B of Fig. 1. Fig. 30 3 represents a vertical central section on the line D—D of Fig. 4; Fig. 4 represents a plan of the ring casting provided with gear wheels *f* and *h*; Fig. 5 represents a detail view partly in vertical section and partly 35 in elevation, showing the sectional sand chute, roller, guide-pins and proximate parts; Fig. 6 represents an external elevation at right angles to Fig. 2, the view being taken from the right side; and Fig. 7 represents an under view of receptacle 8 from 40 which the sand is fed down to chute 10 (see Figs. 2 and 5). For the sake of clearness the chute is omitted from this figure.

a is a circular table, provided with a series 45 of symmetrically disposed openings *b* to receive the bottom pattern plates *c*, and supported loose, *i. e.* capable of being rotated, on a cylindrical support *d* cast on or attached to a central pillar *e*. The table is 50 intermittently rotated by means of so-called mutilated gearing *h* turning with toothed wheel *f*, carried in a circular race *g*, and constantly rotated from a first motion shaft *h'* situated in any convenient position radial

to the center pillar *e*, by means of a pinion 55 B, Figs. 1 and 3.

The use of so-called mutilated gearing for intermittently rotating foundry molding tables is not new, and a construction of such is hereunder described in detail for the purpose of more clearly and completely describing this improved machine.

The ring carrying or forming the wheel *f*, has an inner curved row of teeth, extending over a portion only of the circumference, 65 and forming the so-called mutilated gear wheel *h*. For the sake of illustration merely, the teeth are supposed to extend over three sevenths of the circumference and to number, say 54. A pinion *i* having 18 teeth and 70 mounted on a countershaft *j*, gears with the teeth of the mutilated wheel *h*; so that the countershaft *j* makes three revolutions during three sevenths of each revolution of the wheel *f*, and remains stationary during four 75 sevenths of each such revolution. As shown, a second countershaft *k* is geared by equal sized wheels *l* with the countershaft *j*, and carries a pinion *m*, provided with 14 teeth, gearing with the toothed wheel *n*, having 80 126 teeth, attached to the table *a*. As the shaft rotates three times before becoming stationary, it moves the table one third of a revolution between each stoppage, corresponding to the division of the table between 85 the centers of the successive openings *b*, so that during a complete revolution of the table *a*, it stops three times; the ratio of the times of moving and stopping being 90 as three to four.

The bottom pattern plates *c* are carried level with the table by a carriage *o*, supported on antifriction rollers *p*, which run upon a circular track *q*, carried by conveniently placed standards *r*, except when 95 the pattern plates are beneath the press, when the bearing lugs *s* of the carriage *o* rest directly on the supports or standards *r*.

t are the mold boxes, the sides of which rest partly on the table and partly on the 100 pattern (bottom) plates *c*.

u are the pressing plates, carried by the press crosshead *v*, guided in slides *w*. The crosshead is raised and lowered by connecting rods *x*, actuated by the toothed crank 105 pin disks *y* fixed on the shaft *z*. The toothed disks *y* having 60 teeth, gear the pinions 1 having 20 teeth. The pinions 1

are mounted on a countershaft 2 provided with a pinion 3 having 18 teeth, the pinion 3 gearing with the 54 teeth of the mutilated wheel h at a time when the latter does not 5 actuate the mutilated gearing h previously described for rotating the table a .

Immediately on leaving the last press, each bottom pattern plate c passes over the depressed portion q^1 of the circular track q 10 Fig. 6, so that the top of the pattern plate passes beneath a brush, which sweeps off any loose grains of sand. The brush may be flat, stationary or movable. As shown 15 the brush 4 is cylindrical, carried on the fixed spindle 5 and rotated when a bottom pattern plate passes beneath it by a pinion 6 attached to the brush, gearing with the corresponding one of, in the case illustrated, three racks 7, fixed to the underside of the 20 table a .

As the carriage o rises from the depressed part q^1 of the track, it raises the bottom pattern plate c again flush *i. e.* level with the table a . The mold box t can be drawn away 25 from the opening b , as soon as the pattern plate is lowered quite clear of the molded under surface of the sand in the mold box; and is replaced by a fresh mold box before reaching the first sand supply chute. 30 8 is a tank or receptacle containing the supply of sand, and provided with two or more openings 9 according to the number of chutes 10. Each chute 10 is provided with a tapering lower section 10 a , hinged thereto 35 at 23 and arranged at an angle for convenience of delivery.

11 is a circular channel attached to the underside of the receptacle 8 and passing beneath the openings 9.

40 12 are two or more scrapers according to the number of chutes, and which sweep around the channel 11 (Fig. 2) pushing the sand into the different chutes, as the molding boxes come beneath the respective chutes. 45 The inner side of the channel leaves a gap between its upper edge and the bottom of the receptacle 8 for the arms 13 carrying the scrapers 12. The arms 13 are driven around at the same angular speed as the table by 50 means of a gear wheel 14 attached to the table, pinion 15, vertical shaft 16 and pinion 17, gearing with a gear wheel 18, carried from the center plate 19, from which the arms radiate. The boss of the center plate 55 is formed in two halves bolted together and is carried on a turned flange and bearing 20 at the upper end of the center pillar e .

As shown in Figs. 1 and 7 21 is an automatically moved slide or shutter for regulating the amount of sand allowed to pass down the chute, the opening movement being effected by lever or bar 21 b , mounted on pivoted links 21 c , said bar being in contact at one of its ends with, and actuated by, a 60 cam or tappet 21 c on the ring carrying the 65

gear wheel 18 and the closing movement being effected by a spring 21 d , preferably duplicated as shown in Fig. 7. The lower end of the lower section 10 a of the chute is in position for contact with guide-pins 22 of the 70 mold boxes, but its flexible attachment 23, already mentioned, to the rigid main section of said chute permits said lower section to yield on contact with one of said pins, so that its lower end may clear the 75 same.

In some cases I propose to effect the pressing of the first layer of sand by a roller 24, carried by arm 25, hinged to a bracket 27 80 preferably attached to a support 26 rigid with the previously mentioned cylindrical support d , which is cast as part of the pillar e as shown in Fig. 2. The hinging of the arms 25 allows of the roller automatically adjusting its height and clearing the guide 85 pins 22 of the mold boxes.

Referring to Fig. 1, the empty mold box is placed on the table at the position marked I, and passing the position marked II receives the first layer of sand from the adjoining chute, and then passes beneath the roller 24 by which it is spread out. It next passes beneath the second chute at the position marked III, where it receives a second layer of sand; and thence to the first 95 press where it remains stationary while the sand is being pressed; the toothed portion of the wheel h passing beneath the pinion 3, see Fig. 2, and the mutilated or toothless portion passing beneath the pinion i . While 100 the table is thus stationary, a second mold box is placed over the next succeeding opening at the point marked I. On leaving the first press, the first mold box passes beneath the chute at the position marked IV, 105 receiving the last layer of sand, and then reaches the last press; where the table remains stationary during the pressing. At this time a third mold box is placed over the third opening at the position marked I, 110 while the second mold box is under the first press.

On leaving the last press the carriage supporting the bottom pattern plate moves over the depressed portion of the race q , so that 115 the top of the pattern plate is swept by the brush 4. At the same time the mold box with the sand is removed, and replaced by a fourth mold box, which follows the course just described for the first box. When the 120 fourth mold is at the position marked I, the second and third mold boxes are respectively 125 under the second and first presses.

Where the articles to be cast require a two part mold, the contour of the bottom pattern plates is such as to form the upper part of the mold; while the contour of the underside of the pressing plates is such as to form the lower part of the mold. The pressing plates 130 of the first press and intermediate press,

where three presses are used, may be only approximately contoured to the shape of the bottom part of the mold; the press plate of the last press however being accurately contoured. As the mold boxes are removed they are placed one on the top of the other to form a pile ready for the casting operation. Where the articles require only one part molds, the pressing plates are quite flat.

10 I am aware that prior to my invention brick presses have been proposed, in which the edges of the sand filled mold have received a preliminary pressing, the space so obtained being filled up with sand and the 15 mold box transferred to a second press acting over the whole surface of the sand, for the purpose of producing bricks denser and harder around the sides and ends. I do not therefore claim such, but

20 What I do claim and desire to secure by Letters Patent is:—

1. In a foundry molding machine, the combination of a rotatable table having a series of openings, mechanism for rotating said table adapted to temporarily stop the same during each rotation as many times as the number of such openings, provided with patterns and individually fitting such openings, mold boxes surrounding the latter, 30 means for automatically applying sand to said patterns and means for pressing the sand therein and completing the mold, these means for filling and pressing being arranged for alternative action to supply and 35 press successive layers of sand in order that all parts of the filling may be perfectly packed during a rotation of the table.

2. In combination with an intermittently rotated table provided with openings, mold 40 boxes adapted to surround the same, pattern plates fitting said openings, spouts for supplying the mold box with a layer of sand corresponding to each pause in rotation, presses arranged alternately with respect to 45 said spouts to act on each layer after it is supplied and means for lowering each of said pattern plates from its opening after the work of filling and pressing has been completed.

50 3. In combination with a mold-carrying table and mechanism for rotating it, with several stops during each rotation, means for supplying a layer of sand to each mold box, means for pressing each layer at each 55 stop after it is thus supplied and helping to form the upper part of the mold, pattern plates carried by said table and constituting the bottoms of the mold boxes and means for automatically removing said pattern plates 60 after such pressure for the purpose set forth.

4. In a foundry molding machine, the combination of an intermittently rotated table provided with three or more openings, a succession of vertically movable bottom pattern 65 plates, fitting said openings, two or more

automatically controlled sand delivery chutes and two or more succeeding presses alternating with said chutes and pressing plates attached to said presses, substantially as and for the purpose set forth.

70

5. In a foundry molding machine the combination of an intermittently rotated table provided with a series of openings, with vertically movable bottom pattern plates fitting in said openings respectively, mold 75 boxes each of which surrounds one of said openings, actuating gearing for the press below mentioned, a table driving rack, a circular first motion rack, so-called mutilated gearing between the said table driving rack 80 and said circular first motion rack, and also between the press actuating gearing and said circular rack, a sand supply tank or receptacle, an automatically controlled delivery chute from said tank to the top of each mold 85 box, a press or pressing device situated between each pair of successive delivery chutes and after the last delivery chute, a pattern plate supporting race having a depressed portion immediately after the last press, and 90 a sweeping brush situated above the pressing plate when the latter is on the depressed portion of said race; all substantially as and for the purpose of obtaining greater uniformity in the density of the sand by filling 95 and pressing the sand into and in the mold boxes simultaneously in successive stages.

6. In a foundry molding machine, the combination of an intermittently rotated table having three or four symmetrically disposed 100 openings therein, a series of mold-boxes arranged respectively at said openings, a corresponding series of vertically movable pressing plates arranged to descend therein for forming the lower part of a mold, the 105 said plates being provided with pattern surfaces and the pressing plate of the last press exactly corresponding in the contour of its pattern surface to that of said mold, but the other pressing plates of the series having 110 pattern surfaces which correspond only approximately to that of said mold.

7. In a foundry molding machine having an intermittently rotated table the combination of two or more presses, a sand delivery 115 chute on the approaching side of each press, a sand supply receptacle, having openings in the same to the upper end of each chute, rotating scrapers and an automatically operated shutter situated at the upper end of 120 each chute.

8. In a so-called mutilated gear wheel device for intermittently rotating the mold box carrying table of foundry molding machines, the combination of said table with a ring arranged to drive the same and having a complete outer circle of teeth and an inner partial or mutilated circle of teeth, a driving pinion geared to said outer circle of teeth, a gear wheel attached to said table, a pair of 125 130

countershafts geared together and arranged as described, a pinion on the one countershaft arranged to gear with said mutilated circle of teeth, and a pinion on the other countershaft geared to the wheel attached to the table, substantially as set forth.

9. In a foundry molding machine the combination with an intermittently driving mutilated gear wheel device, of a countershaft, 10 a pinion on the same geared with the mutilated gear wheel of said device, a pair of pinions on the ends of said countershaft and

press actuating toothed crank disks geared with said pinions, all in combination and substantially as and for the purpose set forth.

In testimony whereof I have signed my name to this specification in the presence of two subscribing witnesses.

WILLIAM DAVEY ODDY.
